Application March 29, 1932, Serial No. 601,752

17 Claims.

(Cl. 82—2)

More particularly the invention relates to a lathe of novel and simplified construction embodying improved means for actuating the spindle and tool supports and for obtaining simplicity in the operation thereof.

An object of the invention is to provide a new and improved lathe which is simple and rugged in construction, which embodies front and rear tool supports together with a unitary mechanism for actuating said supports either manually or automatically and which has a feeding mechanism which may be readily modified for changing the set-up of the machine.

Another object is to provide a new and improved lathe embodying a high speed spindle and novel means for driving the spindle at speeds varying over a wide range with extreme smoothness of operation.

Another object is to provide a lathe having a new and improved feeding mechanism providing a wide range of feed speeds, together with novel control mechanism for obtaining extreme simplicity in the operation thereof.

In the exemplary embodiment of the invention, an extreme smoothness of spindle operation and the wide range of spindle speeds is obtained by using a multiple belt in the final drive to the spindle, and in combination with pick-off or change gears. The smoothness of operation resulting from using belts intermediate the gears and spindle is particularly desirable in order to obtain a high finish on the work piece, especially when the machine is used for turning operations employing a high spindle speed and a very fine or slow feed of the tools.

Further objects and advantages will become readily apparent from the following detailed description taken in connection with the accompanying drawings, in which:

Fig. 1 is a front elevation of a preferred form of the invention.

Fig. 2 is a plan view thereof.

Fig. 3 is a right-hand end elevation.

Fig. 4 is a sectional view along the line 4—4 of Fig. 1, illustrating the actuating and clamping means for the tailstock sleeve.

Fig. 5 is a transverse section through the rear tool support.

Fig. 6 is a vertical longitudinal section through the headstock.

Fig. 6a is a fragmentary section through a modified form of adjustable pulley.

Fig. 7 is a vertical transverse section through the headstock.

Fig. 8 is a fragmentary front elevation partly

in section approximately along the line 8—8 of Fig. 7.

Fig. 9 is a fragmentary plan view partly in section approximately along the line 9—9 of Fig. 8.

Fig. 10 is a fragmentary elevation looking at the right-hand end of Fig. 8.

For purposes of disclosure there is illustrated in the drawings and hereinafter described in detail a preferred embodiment of the invention, with the understanding that it is not intended to limit the invention to the particular construction and arrangement shown, it being contemplated that various changes may be made by those skilled in the art without departing from the spirit and scope of the appended claims.

In the form illustrated in the drawings, the invention is embodied in a lathe comprising generally (Figs. 1, 2 and 3) a bed 10 supported on legs 11 and having a headstock 12 at one end thereof in which a spindle 13 is rotatably mounted on a horizontal axis. A front carriage or tool support 14 is mounted for movement longitudinally of the bed on ways 15 (Fig. 3) and carries a cross slide 16 which is adjustable transversely of the spindle axis by means including a handle 17. A rear carriage or tool support 20 is mounted on ways 21 along the rear upper portion of the bed 10 and is arranged to be clamped to the bed in its adjusted position by means of screw devices 22 and a gib 23. A rear cross slide 24 is mounted on the carriage 20 for movement transversely of the spindle axis. Preferably a tailstock 25 is also mounted on the ways 21 so as to be adjustable longitudinally relatively to the headstock spindle 13 and has a center 26 carried in a longitudinally adjustable sleeve 27.

In the exemplary form of the invention the head-stock spindle 13 (Figs. 1 and 6) is arranged to be driven at relatively high speeds from a motor 30 suspended beneath the bed 10. The shaft of the motor carries a multiple V-groove pulley 31 which is connected to a similar pulley 32 on a horizontal shaft 33 by means of a plurality of belts 34. The shaft 33 (Fig. 6) and a parallel drive shaft 35 are formed on their outer ends for the reception of interengaging pick-off gears 36 and 37 respectively. The shaft 35 also has mounted thereon an adjustable V-groove pulley 38.

Preferably the spindle 13 and also the tool supports are actuated from the shaft 35. As illustrated most clearly in Fig. 6 a multiple V-groove pulley 40 somewhat in the form of a sleeve is rotatably mounted on the spindle 13 by means of bearings 41. This pulley is connected to the 55

adjustable pulley 38 by means of a plurality of belts 42. At its right-hand end the pulley 40 has a projecting annular portion 43 carrying one element 44 of a disk type clutch, the other element 5 of which is secured to the spindle 13 and arranged to be actuated by means of a peripherally grooved slideable member 46. Preferably the slideable member 46 is arranged also to actuate a disk type brake, one element of which 10 is secured to the spindle, and the other element 48 of which is stationarily mounted on the headstock. Thus by shifting the member 46 in one direction the power drive is disengaged and the spindle is stopped, whereas by shifting the member 46 in the opposite direction, the brake is released and the clutch engaged to rotate the spindle.

In order to insure a continuous and smoothly operable drive for the spindle, means is preferably provided for taking up slack in the belts 20 42 and also in the belts 34. As illustrated herein the pulley 38 comprises a plurality of disks 50 the surfaces of which are beveled adjacent the peripheries so as to provide V-grooves 51. These 25 disks are keyed to the shaft 35 and are positioned longitudinally on the shaft by means of nuts 52 and 53 formed integrally with the end disks. The disks are of such a thickness that normally they are spaced apart longitudinally of the shaft, the 30 belts 42 holding the disks in laterally spaced relation. As the belts wear or stretch the slack may be taken up by turning one or both of the nuts 52, 53 so as to move the disks closer together and increase the effective diameters of the V- 35 grooves. In order to take up slack in the belt 34, the motor 30 is mounted on a base 56 (Fig. 3) which is pivoted at one end on a rod 57. The other end of the base has a bifurcated lug 58 straddling a vertically extending screw device 59 40 and may be adjusted vertically by means of nuts 60 to change the distance between the motor shaft and the shaft 33.

In some instances where the wrapping of the belts 42 around the adjustable pulley is less than 45 180° a modified construction, such as that illustrated in Fig. 6a, is preferable. In this form rubber or other resilient rings 50a are inserted between the adjacent disks 50 so as to maintain the disks in substantial alinement. These rings 50 are of such a character as to permit the end disks 50b to be adjusted toward each other for the purpose of taking up the slack in the belts. As illustrated in Fig. 6a the left end disk is screw threaded directly onto the shaft 35 and is provided with a set screw for holding it in its adjusted position.

Preferably the tool supports are arranged to be actuated manually by means including a hand wheel 65 (Figs. 1, 2 and 7) or automatically by 60 a driving connection with the shaft 35. In the form of the invention disclosed herein the hand wheel 65 is mounted on the forward end of a transversely extending shaft 66. A pinion 67 on this shaft is arranged to mesh with a rack 68 which is slidably mounted on the bed 10 in a 65 longitudinally extending groove 69. This rack is adjustably secured to the front carriage 14 by a plurality of screw devices 70 (Fig. 1), the rack being provided with a plurality of sets of spaced tapped holes 71 so as to permit adjustment of the rack relatively to the carriage.

The automatic or power driven means for actuating the tool supports includes a worm 75 (Fig. 6) on the shaft 35. This worm meshes with 75 a worm wheel 76 secured to a vertical shaft 77,

A worm 78 on the shaft 77 meshes with a worm wheel 79 on a transversely extending power shaft 80, the rear end of which projects into a casing 81 (Figs. 2, 3 and 7) mounted on the rear surface of the headstock 12. As illustrated most clearly 5 in Fig. 7, the worm wheel 78 is rotatably mounted on the power shaft 80 and is arranged to be connected to said shaft by means of a feed clutch 82, one element 83 of which is secured to the worm wheel 79, and the other element 84 of 10 which is splined to the shaft 80 by means of a plurality of splines 85 so as to be slideable relatively to the element 83. At its rear end the power shaft 80 carries a pick-off gear 86 positioned in the casing 81 and meshing with a 15 companion pick-off gear 87 detachably secured to the rear end of the manually operable shaft 66. Thus when the feed clutch 82 is engaged the front carriage is actuated automatically by a driving connection with the motor 30 and when 20 the feed clutch 82 is disengaged the front carriage may be actuated manually by means of the hand wheel 65.

In the preferred embodiment of the invention, the rear cross slide is also arranged to be 25 actuated from the power shaft 80. Thus, as illustrated most clearly in Figs. 5 and 7, a short transversely extending shaft 90 is rotatably mounted in the casing 81 and carries a detachable pick-off gear 92 which meshes with a companion pick-off gear 93 secured to the rear end of the power shaft 80. The shaft 90 also has a pinion 94 thereon engaging rack teeth 95 formed on the under side of a bar 96 which is slideable longitudinally of the bed 10 in a housing 98 35 (Figs. 2 and 3). This bar is slidably mounted in a recess 97 in the casing 81 (Fig. 7) and in an aligned recess 98 (Fig. 5) in the rear carriage 20, and also has rack teeth 99 formed on its upper surface. The teeth 99 mesh with a gear 100 40 formed on a cylindrical cam 101 which is rotatably mounted on the carriage 20 on a sleeve 102. This cam is provided with a slot 103 which preferably has dwell portions at each end thereof, and in which a roller type cam follower 104 engages. 45 The cam follower 104 is secured to the rear cross slide 24 and preferably is adjustably secured thereto. As illustrated in Fig. 5, the cam follower 104 is mounted on a member 105 which is slidably mounted on the slide 24 and secured 50 thereto by means of an adjusting screw device 106 and a clamping bolt 107.

In the form of the invention illustrated herein, the tool supports may be operated manually for the purpose of bringing the tools up to the 55 work and for returning the tools to their withdrawn positions after the cutting operations have been completed, the tool supports being actuated automatically by means of the power driven mechanism during the cutting operations. In 60 order to avoid injury to the work pieces and to enable the machine to be operated at a relatively high speed, means is preferably provided for automatically engaging the power driven feed mechanism prior to engagement of the tools with 65 the work piece, and to disengage the said mechanism at the end of the cutting operations. Thus the operator by actuating the hand wheel 65 may bring the tool supports rapidly toward the work without fear of improper contact of the tools with 70 the work, and furthermore the completion of the cutting operation is indicated by the tripping out of the power feed mechanism so as to enable the operator immediately to return the tool supports.

The automatic control mechanism is prefer- 75

ably arranged to govern the operation of the feed clutch 82 and also the spindle clutch and brake mechanism and, as illustrated in the drawings, comprises a member or bar 110 (Figs. 1 and 6 to 9) which extends transversely in the bed and is slidably mounted therein for reciprocatory movement in a front to rear direction. At its rear end the member 110 is operatively connected to a vertically extending control shaft 111 which carries 10 and arm 112 on its lower end having a bifurcated portion 113 fitting between collars 116 on the member 110. The control shaft 111 has mounted thereon two clutch operating elements 117 and 118. The element 117 is in the form of a clutch yoke having portions engaging the peripherally grooved actuating element 119 mounted on the power shaft 80 and arranged to operate the feed clutch element 84. The clutch operating element 118 is positioned above the element 117 on the shaft 111 and is also in the form of a yoke and has portions engaging the peripherally grooved actuating member 46 which controls the operation of the spindle clutch and the spindle brake. At its upper end the control shaft 111 carries a 25 manually operable handle 122 which extends forwardly over the headstock so as to be within easy reach of an operator in front of the machine. Thus the spindle clutch and brake mechanism and the feed clutch may be operated manually by 30 means of the handle 122 or automatically, as hereinafter more fully described, by means of the member 110. The control shaft 111 is normally urged to its clutch disengaging and brake applying position by means of a coiled spring 125 surrounding the member 110 intermediate a collar 126 and the forward wall of the bed 10. Furthermore the elements 117 and 118 are preferably so positioned on the control shaft 111 that the spindle clutch will be engaged prior to the 35 engagement of the feed clutch, and the spindle clutch will be disengaged after the disengagement of the feed clutch so as to insure operation of the spindle before the tools engage the work and to permit the spindle to operate a short time after the completion of the feeding movements of the tool supports and permit the tools to clear the 40 cut. As illustrated in Fig. 7, a coiled spring 128 is positioned intermediate the element 119 and the feed clutch member 84 so as to provide a lost motion connection between these parts and prevent any jamming should the teeth of the feed clutch fail to mesh instantaneously when the feed clutch 45 is engaged.

As mentioned hereinbefore the control member 110 is normally urged to its rear position by means of the coiled spring 125 to disengage the 50 clutches. This member is also arranged to be held in its forward or clutch engaging position during the cutting operation, and as illustrated herein (Figs. 7 to 9), a latch device 130 is 55 slideable vertically on the front surface of the bed 10 and is normally urged to its upper position by means of a coiled spring 131. When the member 110 is in its forward position a portion 132 of the latch device is arranged to engage in a notch 133 in the member 110, thereby to hold the member in the clutch engaging position. It will be readily apparent that in order to disengage the clutches it is merely necessary to depress the latch device 130.

In order to move the control member 110 to its forward or clutch engaging position at the commencement of the cutting operation, a suitable dog is preferably mounted to move with the front tool support 14 and to engage a cam portion 75

135 on the forward end of the member 110. As shown herein a bar 136 is secured to the lower edge of the front tool support 14 and extends longitudinally therefrom in front of the headstock and over the forwardly extending end of the member 110. This bar is provided with a T-slot 137 in its lower surface for the purpose of adjustably supporting a feed dog 138 and a stop dog 139. The feed dog 138 is provided with a cam surface 138' arranged to engage the cam 10 surface 135 of the member 110 and move the control member 110 forwardly. The stop dog 138 is adjusted on the bar 136 to a position wherein a cam portion 139' thereon will engage the upper beveled end 130' of the latch device 130 at the 15 completion of the cutting operations and depress said latch device and thereby disengage the feed clutch and spindle clutches and apply the spindle brake. Preferably the dog 139 has a downwardly extending portion provided with a cam surface 20 139 arranged to engage a second cam surface 135' on the member 110 so as positively to disengage the clutches when the latch 130 is depressed.

In order to permit an operator to disengage the 25 power feed clutch 82 without disengaging the spindle clutch, a manual control device 140 is mounted on a transversely extending rod 141 which is slidably mounted in the headstock and is normally urged to its forward position by a 30 coiled spring 141'. The control device is operable by means of a control handle 142. This handle is pivotally mounted at 143 and has a suitable cam formation on its lower end arranged to engage the end of the rod 141 so that when the 35 handle is swung downwardly from the position illustrated in Fig. 7 the feed clutch is disengaged, the resilient connecting spring 128 permitting the necessary relative movement between the clutch member 84 and the actuating element 119. 40

In order to facilitate the rapid production of finished work pieces the tailstock sleeve 27 (Fig. 4) is preferably arranged to be actuated by means of a manually operable control handle 150 which also serves to clamp the sleeve 27 in its operable 45 position. The handle 150 is pivoted by means of a pin 151 to the upper end of a pinion shaft 152 which carries a pinion 153 meshing with rack teeth 154 on the sleeve 27. The lower end of the shaft 152 is provided with a nut 155 which cooperates with an eccentric cam formation 156 on the lower end of the handle 150 to draw the slide portions 157 of the tailstock 25 together and clamp the sleeve 27 in its adjusted position. By swinging the handle 150 (Fig. 4) in a clockwise direction, as indicated by the arrow, through 50 an angle of 90° the clamping means is released and by then swinging the handle about the shaft 152, the sleeve 27 may be withdrawn.

In order to lubricate the spindle, clutches, brake 60 and the feed drive gearing, an oil throwing device 160 (Fig. 6) is preferably mounted on a short shaft 161 within the bed and driven from the shaft 35 by means of sprockets 162 and 163 and a chain 164. The lower portion of this device is immersed in oil contained in a reservoir 165 formed in the lower portion of the bed. Such a device throws a spray upwardly over all of the parts mentioned and insures constant lubrication of said parts. 65

The lathe disclosed herein is not only simple and rugged in construction and adapted for convenient operation, but is also readily adapted for use in which the work pieces are produced with great rapidity. In such a machine the time lost 70 75

by an operator in manual movements has a very important bearing upon the all-around efficiency of the machine. In the form illustrated herein the sequence of operations by the operator and machine would generally be, first, the placing of a blank work piece between centers by the operator, the work piece being held in the left hand while the tail center is moved into engagement with the work by the right hand, the tailstock center 10 then being clamped also by the actuation of the single tailstock control handle which governs the movement and the clamping of the tailstock center sleeve. Both of the tool supports may then be traversed quickly without fear of driving the 15 tools into the work, the power feed being started automatically when the tools reach a position adjacent the work. The cutting operations are thereupon performed automatically and at the completion thereof the feed and spindle clutches 20 are disengaged and the spindle brake applied automatically, after which the operator returns the tool supports quickly to their withdrawn position by means of the manual control wheel. Then with his right hand the operator releases and 25 withdraws the tail center while with his left hand he removes the finished work piece from the machine.

By mounting the spindle clutch and brake operating members directly on the spindle the entire driving train to the spindle may be kept in motion continuously. This is of particular advantage since it is then only necessary to bring to a stop the spindle and work, with a consequent saving in power and time in starting and stopping the machine.

The combination of a multiple V-type belt and pick-off gears for actuating a spindle, with the belts in the final drive, is effective to prevent chatter and obtain an extremely smooth operation. Furthermore by positioning the pick-off 40 gears for both the front and rear tool supports in the casing 81 at the rear of the machine, a very compact, inexpensive and convenient feed box is provided.

The spindle drive illustrated herein also lends itself readily to modification if it is desired to drive the spindle directly from the motor at a single relatively high speed. In such an instance the shaft 33 (Fig. 6) together with its 45 bearings can be removed and the bearing holes plugged, and three belts 34 would be used and extended upwardly to connect directly to the left end grooves in the spindle pulley 40. The corresponding three left-hand belts 42 would be removed, the adjustable pulley 38 being then provided with merely four disks 50.

We claim as our invention:

1. A lathe having, in combination, a bed, a headstock, a spindle rotatably mounted in the headstock, a longitudinally movable front tool support, a transversely movable rear tool support, means for driving said spindle, and means for actuating said tool supports comprising a transversely extending power shaft carrying two 60 pick-off gears on its rear end, means including a first companion gear meshing with one of said pick-off gears for actuating the rear tool support, a parallel transversely extending shaft carrying a second companion gear meshing with 65 the other pick-off gear, means connecting said parallel shaft to actuate the front tool support, and a hand wheel carried on the front end of said parallel shaft for moving the tool supports manually.

2. A lathe having, in combination, a bed, a

headstock, a spindle rotatably mounted in the headstock, and means for driving said spindle comprising a motor stationed beneath the bed, a horizontal shaft, means connecting the motor and shaft, a parallel shaft, pick-off gears connecting said shafts, a plurality of disks on said parallel shaft having beveled peripheral edges forming a plurality of V-grooves, means for adjusting the outer disks longitudinally of the shaft, a pulley rotatably mounted on the spindle, 10 a plurality of V-belts connecting said pulleys, a spindle brake, a clutch for engaging said spindle pulley and spindle, and means for operating said clutch and brake.

3. A lathe having, in combination, a rotatable 15 headstock spindle, a tailstock center movable toward and from the headstock spindle, means for driving and for stopping the spindle including a clutch and brake, a movably mounted tool support, power means for actuating the tool support 20 during a cutting operation including a feed clutch, single means for advancing the tailstock center and for clamping said center, means for advancing said tool support rapidly at a traverse rate and for engaging said feed clutch automatically, and a control device effective to disengage the spindle clutch and engage the brake subsequent to a disengagement of the feeding clutch.

4. A lathe having, in combination, a bed, a headstock spindle, a longitudinally movable front 30 tool support, a transversely movable rear tool support, means for actuating said spindle, and means for actuating said tool supports comprising a horizontal shaft extending transversely of the bed and projecting forwardly therefrom, a 35 manually operable hand wheel on the forward end of said shaft, a rack secured to the front tool support extending longitudinally along the bed, a pinion on said transverse shaft engaging said rack, a second transverse shaft projecting 40 rearwardly from the bed and alterable change gears connecting said transverse shafts, a short shaft, alterable change gears connecting said shaft with the rear end of said second shaft, and means including a rack and pinion connecting 45 said short shaft to actuate the rear cross slide.

5. A lathe having, in combination, a bed, a headstock spindle, a longitudinally movable front tool support, a transversely movable rear tool support, means for actuating said spindle, and 50 means for actuating said tool supports comprising a horizontal shaft extending transversely in the headstock and projecting forwardly therefrom, a manually operable hand wheel on the forward end of said shaft, a rack secured to the 55 front tool support extending longitudinally along the bed, a pinion on said transverse shaft engaging said rack, a second transverse shaft projecting rearwardly from the bed and alterable change gears connecting said transverse shafts, a short 60 shaft, alterable change gears connecting said short shaft with the rear end of said second shaft, a rack slidable longitudinally on the rear of the bed, a pinion on said short shaft engaging said rack, a cylindrical cam rotatably mounted 65 on a transverse axis and having gear teeth formed thereon engaging said rack, and a follower adjustably secured to the rear cross slide engaging a slot in said cam.

6. A lathe having, in combination, a bed, a 70 headstock spindle, a longitudinally movable front tool support, a transversely movable rear tool support, means for actuating said spindle and tool supports comprising a drive shaft, means connecting said shaft and spindle including a 75

5 pulley rotatably mounted on the spindle and a spindle clutch for engaging said pulley with the spindle, means connecting said drive shaft to actuate the tool supports including a feed clutch for starting and stopping both supports, means for manually actuating said supports when the feed shaft is disengaged, a vertical control shaft in said headstock having an operating handle secured to its upper end, a first member on said control shaft for actuating the spindle clutch, and a second member on said control shaft for actuating the feed clutch.

10 7. A lathe having, in combination, a bed, a headstock, a spindle rotatably mounted therein, a longitudinally movable front tool support, a transversely movable rear tool support, means for actuating said spindle and tool supports comprising a spindle clutch, a spindle brake, a spindle clutch and brake operating member arranged to engage the brake when the clutch is disengaged, a feed clutch, a vertical control shaft in said headstock, said control shaft carrying said operating member, a second member on said control shaft for actuating the feed clutch, and a handle on the upper end of said control shaft for shifting said clutches and brake.

15 8. A lathe having, in combination, a bed, a headstock, a spindle rotatably mounted therein, a longitudinally movable front tool support, a transversely movable rear tool support, means for actuating said spindle and tool supports comprising a spindle clutch, a spindle clutch operating yoke, a feed clutch, a control element in said headstock, said control element carrying said clutch operating yoke, a second yoke on said control element for actuating the feed clutch, and means for automatically shifting said clutches comprising a member slidably mounted on the bed and connected to operate said control element, means normally urging said member to its clutch-disengaging position, a latch device for holding said member in its clutch engaging position, a first dog movable with the front tool support operable when said support is advanced manually to move said member to its clutch engaging position, and a second dog movable with said support arranged to disengage said latch device and clutches.

20 9. A lathe having, in combination, a headstock spindle, a longitudinally movable front tool support, a transversely movable rear tool support, means for actuating said spindle and tool supports comprising a drive shaft, means connecting said shaft and spindle including a pulley rotatably mounted on the spindle and a spindle clutch for engaging said pulley with the spindle, means connecting said drive shaft to actuate the tool supports including a feed clutch for starting and stopping both supports, means for manually actuating said supports when the feed shaft is disengaged, a vertical control shaft in said headstock having an operating handle secured to its upper end, a first member on said control shaft for actuating the spindle clutch, a second member on said control shaft for actuating the feed clutch, and means for automatically shifting said clutches comprising a movably mounted element connected to oscillate said control shaft, means normally urging said element to its rearmost position to disengage said clutches, a latch device for holding said bar in its forward position, a first dog movable with the front tool support operable when said support is advanced manually to move said element to engage the clutches, and a sec-

25 ond dog arranged automatically to disengage said clutches to stop the spindle and support.

10 10. A lathe having, in combination, a bed, a headstock, a spindle rotatably mounted therein, a longitudinally movable front tool support, a transversely movable rear tool support, means for actuating said spindle and tool supports comprising a horizontal drive shaft rotatably mounted longitudinally in the headstock, means connecting said shaft and spindle including a pulley rotatably mounted on the spindle and a spindle clutch for engaging said pulley with the spindle, means connecting said drive shaft to the tool supports including a feed clutch, a vertical control shaft in said headstock having an operating handle secured to its upper end, a first member on said control shaft for actuating the spindle clutch, a second member on said control shaft for actuating the feed clutch, and means for automatically shifting said clutches comprising a bar slidably transversely of the bed, an arm on the lower end of the control shaft to which the rear end of said bar is connected, means normally urging said bar to its rearmost position to disengage said clutches, a latch device for holding said bar in its forward position, a first dog movable with the front tool support operable when said support is moved manually towards the headstock to move said bar to its forward position and engage the clutches and latch device, and a second dog movable with said support arranged to disengage said latch device to stop the spindle and tool supports at the end of a cutting operation.

15 11. A lathe having, in combination, a rotatably mounted work supporting and driving spindle, and means for driving said spindle comprising a motor, a shaft, means connecting the motor and shaft, a parallel shaft, pick-off gears connecting said shafts, and means connecting said parallel shaft and spindle comprising pulleys on said parallel shaft and spindle having a plurality of V-grooves therein, a plurality of V-belts connecting said pulleys, and means for taking up slack in said V-belts.

20 12. A lathe having, in combination, a rotatably mounted work supporting and driving spindle, and means for driving said spindle comprising a motor, a shaft, means connecting the motor and shaft, a parallel shaft, pick-off gears connecting said shafts, and means connecting said parallel shaft and spindle comprising a pulley on said parallel shaft, a second pulley rotatably mounted on said spindle, a belt connecting said pulleys, and a clutch for connecting said second pulley to drive the spindle.

25 13. A lathe having, in combination, a bed, front and rear tool supports movably mounted on said bed, means for rotatably supporting and driving the work, and means for actuating said tool supports comprising a power driven shaft extending transversely in the bed, a pair of pick-off gears for the front tool support one of which is mounted on the rear end of said shaft, means connecting the other gear to drive the front tool support, a second pair of pick-off gears for the rear tool support one of which is also mounted on the rear end of said shaft, and means connecting the other of said second pair of gears to actuate said rear tool support.

30 14. A lathe having, in combination, a bed, front and rear tool supports movably mounted on said bed, means for rotatably supporting and driving the work, and means for actuating said tool supports comprising a power driven shaft extending

- transversely in the bed, a pair of pick-off gears for the front tool support, one of which is mounted on the rear end of said shaft, a shaft parallel to said power shaft carrying the other of said gears on its rear end and extending forwardly from the bed, means connecting said parallel shaft to actuate the front tool support, a second pair of pick-off gears for the rear tool support one of which is also mounted on the rear end of 5 said shaft, and means connecting the other of said shaft, and means connecting the other of said second pair of gears to actuate said rear tool support.
15. A lathe having, in combination, a bed, front and rear tool supports movably mounted on said bed, means for rotatably supporting and driving the work, and means for actuating said tool supports comprising a power driven shaft extending transversely in the bed, a first pair of pick-off gears one of which is mounted on the rear end 10 of said shaft, a shaft parallel to said power shaft carrying the other of said gears on its rear end and extending forwardly from the bed, means connecting said parallel shaft to actuate the front tool support, a second pair of pick-off gears 20 one of which is also mounted on the rear end of said shaft, means connecting the other of said second pair of gears to actuate said rear tool support, and a manually operable wheel secured to the front end of said parallel shaft.

16. A lathe having, in combination, a rotatable headstock spindle, a tailstock center movable toward and from the headstock spindle, means for driving and for stopping the spindle, a movably mounted tool support, power means for actuating the tool support during a cutting operation, a single means for advancing the tailstock center and for clamping said center, means for advancing said tool support rapidly at a traverse rate and for engaging said power means 10 automatically, and control means effective to disengage said power means and to stop said spindle upon completion of a cutting operation and before return of the tool support.

17. A lathe having in combination, a bed, a 15 headstock spindle, a longitudinally movable front tool support, a transversely movable rear tool support, means for actuating said spindle and tool supports comprising a common drive shaft, means connecting said shaft and spindle includ- 20 ing a spindle clutch, means connecting said drive shaft to actuate the tool supports including a feed clutch for starting and stopping both supports, means for manually actuating said supports when the feed clutch is disengaged, and control means 25 for actuating the spindle clutch and for actuating the feed clutch.
